UNITED STATES PATENT OFFICE.

HOWARD M. VARIAN, OF DETROIT, MICHIGAN.

BOILER-TUBE CLEANER.

1,375,123.

Specification of Letters Patent. Patented Apr. 19, 1921.

Application filed March 15, 1915. Serial No. 14,530.

To all whom it may concern:

Be it known that I, HOWARD M. VARIAN, a citizen of the United States of America, residing at Detroit, in the county of Wayne, 5 and State of Michigan, have invented certain new and useful Improvements in Boiler-Tube Cleaners, of which the following is a specification, reference being had therein to the accompanying drawings.

10 The invention relates to boiler tube cleaners of that type in which a series of jet nozzles on a common header is moved successively into registration with different rows of tubes.

15 It is the object of the invention, first, to obtain a construction applicable to boilers in which the smoke box is divided by partitions into a plurality of compartments of varying sizes, and in which the tubes connecting with different compartments may be simultaneously cleaned. It is a further object to adapt the construction for use in connection with the battery of boilers, the tubes of all of which are simultaneously cleaned; 25 further to provide for the simultaneous cleaning of transversely-extending tubes; and further to obtain various advantageous features as hereinafter set forth.

In the drawings:

30 Figure 1 is a section through the smoke boxes of adjacent boilers to which my cleaner is applied; and

Fig. 2 is a transverse section.

A and A' are the smoke boxes of adjacent boilers arranged in a battery, and B are the tubes connecting in to said smoke boxes. The smoke boxes are divided by partitions C into a plurality of compartments D E F, the center compartment E being of 35 greater depth than the side compartments. G are air-heating tubes extending through the smoke box above the tubes B and transversely thereof.

To simultaneously clean the tubes in the 40 various compartments of the several boilers, I have arranged within each smoke box a header H, which extends through the partitions C and across each of the compartments D E F. In each of the compartments 45 there is connected to this header a transversely-extending pipe corresponding in length to the rows of tubes, and in the specific construction shown there are two pipes I and J in each of the outer compartments 50 D and F, and a single pipe K in the center compartment E. The reason for this ar-

angement is that the pipes I J K are designed to be successively registered with vertical rows of tubes B by the longitudinal movement of the header H, and as there are 60 a lesser number of rows in the center compartment than in the side compartments, a single pipe in the latter could not be registered with all of the tubes. However, by placing two or more pipes in the wider compartments, suitably spaced from each other, a movement of the header sufficient for covering the tubes in the narrow compartment will also be sufficient for the tubes of the outer compartments. 65

Each of the pipes I J K is provided with jet nozzles M spaced to register with the tubes in each row. When steam is discharged from these jets there will be a rearward thrust, and therefore to hold the pipes 70 from rearward movement a guide L is provided. This, as shown, is arranged to engage the center pipe K, which is of greater length than the pipes in the side compartments, and as shown the guide is formed of 75 an angle bar extending across between the opposite sides of the chamber. The header H, as shown, is not in the plane of the pipes I J K, but is arranged in front thereof, and is connected to said pipes by horizontally- 80 extending pipes N. These are also provided with jet nozzles O which are directed upward, so that the jets will impinge against the transversely-extending air-heating tubes G. The whole movable structure is supported 85 preferably upon longitudinal guide rods P, upon which the horizontal pipes N rest, while at the rear there is arranged a series of hooked supports Q, which co-operate with the guides L in resisting rearward thrust. 90 R is the steam conduit for supplying steam to the header H. S and S' are swinging conduits connected to the conduit R and together forming a flexible connection, permitting the independent movement of the 95 header H. 100

For operating the headers H there is arranged in the space adjacent intermediate boilers a connecting rack T, which is in mesh with a pinion U actuated by a pulley 105 V and connecting chains V'. The rack-bar T passes through the air conduit W which communicates with the air-heating tubes, and to prevent leakage of air tubes W' are connected into said conduit and form a 110 housing for the rack-bar. The steam pipe R in each boiler is controlled by the valve X,

and these valves are arranged outside of the boilers in position for convenient operation.

With the construction as described in operation, whenever it is desired to clean the tubes it is only necessary to open the valves X, and then to successively adjust the headers H longitudinally by means of the chain pulley V', pulley V and pinion and rack connection. This movement will successively register the jet nozzles of the pipes I J K with the different vertical rows of tubes in all of the boilers, so that the cleaning operation can be quickly and effectively performed. At the same time the upwardly-directed jets in the horizontal pipes N will clean the transversely-extending air-heating tubes G.

As the upper horizontal rows of tubes are of lesser width than the lower rows, and as the outer wall of the smoke box is correspondingly inclined, the outer pipes I are preferably of the bent form shown. Thus the inclined portion of the pipe I will permit said pipe to be moved adjacent to the

outer wall of the smoke box without interference therewith. The structure is strengthened by connecting brace rods Y, which attach this bent pipe to the adjacent pipe J.

What I claim as my invention is:

The combination with a battery of boilers each having a smoke box and tubes opening thereinto, of flue cleaners in said smoke boxes having headers in alinement with each other, an operating connection for said headers arranged in the space between boilers and including a rack-bar connecting said headers, an air conduit at the side of the boiler through which said rack-bar passes, and a tubular housing for said rack-bar in said air conduit, to prevent leakage of air.

In testimony whereof I affix my signature in presence of two witnesses.

HOWARD M. VARIAN.
